US0D1074763S

(12) **United States Design Patent** (10) Patent No.: **US D1,074,763 S**
(45) Date of Patent: ** May 13, 2025

(54) **3D PRINTER**

(71) Applicant: **Shenzhen Elegoo Technology Co., Ltd.**, Shenzhen (CN)

(72) Inventors: **Yongjun Hu**, Chenzhou (CN); **Guizhou He**, Yuanjiang (CN)

(**) Term: **15 Years**

(21) Appl. No.: **29/956,710**

(22) Filed: **Aug. 8, 2024**

(30) **Foreign Application Priority Data**

Jul. 9, 2024 (CN) 202430426019.7

(51) **LOC (15) Cl.** **15-09**

(52) **U.S. Cl.**

USPC **D15/122**

(58) **Field of Classification Search**

(57) **CLAIM**

The ornamental design for a 3D printer as shown and described.

DESCRIPTION

FIG. 1 is a front, right, and top perspective view of a 3D printer, showing our new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the 3D printer that form no part of the claimed design.

1 Claim, 8 Drawing Sheets
